UNITED STATES PATENT OFFICE.

WILLIAM H. NOBLES, OF ST. PAUL, MINNESOTA.

IMPROVED STEAM DREDGING-BOAT.

Specification forming part of Letters Patent No. **55,347**, dated June 5, 1866.

To all whom it may concern:

Be it known that I, WILLIAM H. NOBLES, of St. Paul, Ramsey county, State of Minnesota, have invented an Improved Steam Dredging-Boat for Channeling Rivers; and I do hereby declare the following to be an exact description thereof, reference being had to the accompanying drawings, and to the letters of reference marked thereon, making a part of this specification, in which—

Figure 1 represents a top view, and Fig. 2 a side elevation, of the boat, and Figs. 3 and 4 the shape of the plows.

The nature of my invention consists in the wheels being set diagonally or straight across the boat, having the plows arranged spirally around the wheels, that revolve in apertures of the frame in front of the boat, or straight across the center of the frame, to be operated by steam-power.

A represents the shape of the boat. B are the supports of the frame C in front, and to which frame or platform C the engines and dredging-machine are attached.

D represents the engines, and E the wheels, set obliquely or diagonally; or they may be set parallel with the square end of the stern of the boat. The center beam of the frame C is pivoted at the center of the bow at G. H represents the shaft or axis of the wheel E, and J represents the cranks attached to the engines D.

The plows L are somewhat similar to the curved shape of an ordinary plow, but are set obliquely on the post or arm M, the arms being fastened to the buckets or frame-work N of the wheels permanently by strong clips, and supported in their places by a back strip, the mortise P fitting to the axle H; and the second mortise P also fits on the axle H when the shovels or plows are to be extended for the purpose of digging the channel deeper. These plows are attached to the wheel in a spiral form, so that the second plow throws away to one side the earth thrown up by the first furrow. The earth is thus thrown to each side of the boat, instead of piling up the dirt on a line with the square stern of the boat.

The advantage of my invention being to channel on each side of the center of the boat, according to the curving stream, either side working faster or slower, so as to conform with the inner or outer radius of the curve of the stream, to go counter to which would only refill the channel. I have ballast movable boxes

or cars R on the deck of the boat, so as to regulate the depth of the boat required, changing the depth of the channel without being compelled to change or extend the shovels at every little variation in the bed of the river, by moving the boxes R from the bow to the stern, and vice versa, as shown by the dotted lines marked S.

Another advantage is that in strong currents my diagonal or oblique wheels will operate effectually without the use of steam, by the force of the current operating on the buckets of the obliquely-set wheels, preventing the accumulation of earth at the center of the channel.

I also permanently place a double-mold-board plow, T, in the front of the boat, between the wheels E, so as to remove any ridge of dirt that may accumulate between the inside ends of the wheels that may not have been reached by the plows on the wheels, or what the wheels may have failed to cut.

V are the ordinary feed-works, with the anchor-ropes W attached.

The upper works or frame, to which the wheels, plows, or screws are attached, is so made as to cover a much more extended surface than the hull of the vessel, so that when the machinery is in motion it will operate outside and beyond the hull of the vessel, and the sand or earth removed by such operation so far to either side as will admit a free passage, and so as to make any desirable curve corresponding with the draft or current of the stream.

What I claim as my invention, and desire to secure by Letters Patent, is—

1. The wheels E, operating in square apertures, and located either obliquely or straight across the boat, having their plows L set spirally and obliquely, so as to make a clear channel and throw the dirt to each side of the boat, when said devices are combined with the upper works or frame of a vessel greater in extent than the hull thereof, as herein described.

2. The combination of the spirally-set plows L, platform C, and center plow, T, when arranged upon a boat, as herein described, and for the purposes set forth.

W. H. NOBLES.
